UNITED STATES PATENT OFFICE.

HORACE CAVELL JEAFFRESON, OF LONDON, ENGLAND.

LOCKING DEVICE FOR BAGS AND THE LIKE.

1,262,053.

Specification of Letters Patent.

Patented Apr. 9, 1918.

Application filed December 26, 1917. Serial No. 208,918.

To all whom it may concern:

Be it known that I, HORACE CAVELL JEAFFRESON, a subject of the King of Great Britain and Ireland, residing at 176 Pentonville road, King's Cross, London, N., England, have invented certain new and useful Improvements in Locking Devices for Bags and the like, of which the following is a specification.

- 10 This invention relates to safety locking or securing devices for bags and the like of the kind in which a hinged ring loop or link is arranged to be slipped over the usual interlocking spring knobs or balls of the closing device in order to safeguard the latter against unintended or accidental opening due either to wear or to the bending of the knob stems or to strain on or bending of the frame or other causes.
- 15 20 Now, according to this invention I secure to one of the locking members a ring, link or catch adapted to be turned over both knobs when the latter are employed as a closing device automatically as the latter is actuated during the closing operation.

In a practical embodiment of my invention the stem carrying one of the knobs or balls is pierced below the knob and a split ring is threaded through the passage so provided, so as to be hinged therein.

Moreover, a lug or projection may be arranged on the bag-frame so that the ring will be caused to engage it as it is swung upward and over the two knobs or balls when the two frame parts of the bag are pressed together. This lug or projection may be arranged on the bent portion of the stem of the second knob, or that portion of the stem which is soldered or secured to the frame, or it may be a part of or on the bag frame.

The exact position where the ring, link or catch is secured to the knob, stem or bag frame will be determined by the size, height or position of the interengaging knobs or locking members.

To open the bag it is only necessary to throw back or disengage the catch or ring and press the knobs apart, in the usual manner.

The ring itself may be in the form of a transversely or circumferentially split ring, and while, preferably, of circular form it may, in some cases, be of oval or other shape.

In order that the hole to be bored in the stem of the knob may be as small as possible so as not to unduly weaken it, I may employ a circumferentially split ring or double wire coil having only a single thickness at that portion where the ring passes through the stem.

The invention will now be described with reference to the accompanying drawings, which illustrate an embodiment thereof.

Figure 1 shows the members of a bag frame with the usual locking balls opened, and a split ring arranged according to this invention in its inoperative position.

Fig. 2 shows the bag frame closed but not locked, and

Fig. 3 shows the ring in locking position and the bag frame slightly opened.

Fig. 4 shows one form of projection to cause the ring to automatically lock when the bag is closed.

Fig. 5 is a perspective view of a modified constructional form of the invention.

Fig. 6 a front view of the same showing the parts during the closing action.

Fig. 7 is a lateral view showing the parts closed, and

Fig. 8 is a plan view of Fig. 7.

Referring first to Figs. 1, 2 and 3, *a*, *a'* represent the upper portions of the two members constituting a bag frame. *b*, *b'* are the interengaging knobs of well-known construction carried on stems *c*, *c'* soldered or otherwise secured to the members *a*, *a'* respectively.

Hinged or pivoted in or on one of the stems *b'* is a split ring *d* of strong thin material, so that the stem is not seriously weakened by the hole *c*² in which the ring is rotatably held. The ring is of such diameter that when the knobs are in interlocking engagement and the ring is swung over gently it is capable of clearing the knob *b*, preferably with a slight frictional or springy action, before dropping into the position shown in Fig. 3, in which the bag mouth is locked thereby. To open the bag the ring must first be slipped off the knob *b*, and then the two knobs *b*, *b'* pressed apart in the usual manner.

The ring *d* conveniently consists of a double coil of thin spring wire, except at the part seated in the hole *c*² when it is of single thickness, as shown in Fig. 1.

Instead of a ring, a link, hook or cap may be arranged in a similar manner to secure the two knobs together.

As shown in Fig. 4, the stem *c* is formed with a projection *c** on its upper surface to serve as a guide for the ring as the latter is thrown upward into locking position over the knobs automatically in the closing movement of the latter. During this movement the knob *b'* in approaching the knob *b*, see Fig. 4, carries the ring *d* toward the lug or projection *c** so as to raise its free end and at the same time to impede its further displacement for a moment in opposition to its resiliency so that in the next instant, during which the knob *b'*, after passing the knob *b* and snapping in front of it, (Fig. 2), with the usual quick forward jerk, due to the resiliency of the stems, the momentum of inertia thus imparted to the ring coupled with the resiliency previously stored therein causes the ring to fly over both knobs and to assume the safe locking position.

In the constructional form shown in Figs. 5 to 8 the security member has the form of a loop *d'* which is actually hinged in a bore *b*² in the knob *b*. To provide for the guidance of the loop during its oscillation about its hinge the knob *b* is laterally cut away on each side as shown at *b*³, and an offset or abutment *b*⁴ is maintained to limit this movement in upward direction. The function of the projection *c** is here actually performed by the knob *b'* which, as it approaches the knob *b* (Fig. 6) during the closing of the bag, strikes the loop *d* so as to cause the latter first to swing up into the position shown in dotted lines in Figs. 6 and 7 against the abutment *b*⁴ and from this position to drop automatically over the

knob *b'* impelled by the sudden jerk as the knobs snap one behind the other and aided by gravity in this action.

What I claim and desire to secure by Letters Patent is:—

1. A locking device for bags and the like comprising in combination with a closing device, such as knobs adapted to engage one with the other when in the closing position of a ring, catch arranged on one of the members or on the bag frame so as to be thrown into engagement with and to secure the closing device in its closed position automatically by the closing action of the latter.

2. A locking device for bags and the like as set forth in claim 1, having means adapted to assist or to guide the locking device automatically to engage the closing device during the closing of the latter.

3. A locking device for bags and the like as set forth in claims 1 and 2 in which the locking member is in the form of a ring of spring wire freely pivoted or hinged and adapted to coöperate with a guide during the closing action of the bag so as to fly over and to embrace the closing device.

4. A locking device for bags and the like as set forth in claim 1 in which the loop is hinged in one of the knobs and the latter is provided with parallel cheeks or a guide for the upward movement of the loop and with a stop or abutment adjacent thereto for limiting that movement.

In testimony whereof I have affixed my signature in presence of two witnesses.

HORACE CAVELL JEAFFRESON.

Witnesses:

JUSTIN E. POLLEY,
STANLEY D. DICKER.
